UNITED STATES PATENT OFFICE.

WALTER L. SMITH, OF CHICAGO, ILLINOIS, ASSIGNOR TO HENRY DATE, OF AUSTIN, ILLINOIS.

MEMORANDA-FILE.

SPECIFICATION forming part of Letters Patent No. 623,046, dated April 11, 1899.

Application filed September 3, 1898. Serial No. 690,168. (No model.)

To all whom it may concern:

Be it known that I, WALTER L. SMITH, a citizen of the United States, and a resident of Chicago, county of Cook, and State of Illinois, 5 have invented certain new and useful Improvements in Memoranda-Files, of which the following is a specification, and which are fully illustrated in the accompanying drawings, forming part thereof.

10 My invention relates to that class of files adapted particularly for use in connection with literary work and intended for the reception of memoranda, clippings, &c.; and its objects are to provide an improved form 15 of case, so that a plurality of cases of corresponding configuration may be placed side by side upon the shelf of a cabinet and each may be removed therefrom without disturbing its companions; to provide an improved form of 20 removable pocket for the case, so that slips may be readily inserted within the pocket without removing the same from the case and may be easily discharged therefrom when the pocket is removed, and to provide a suitable 25 index for each case so related to the several pockets of the case that the latter may be individually distinguished at a glance. These several objects are attained in the construction hereinafter fully described, and 30 which is fully illustrated in the accompanying drawings, in which—

Figure 1 is an isometric view of the case, taken oblique to three of its sides. Fig. 2 is a detail plan section of a cabinet, showing a 35 number of my improved cases arranged upon the shelf thereof; and Fig. 3 is a detail perspective of one of the removable pockets.

The case L is oblong-rectangular in form, and preferably of greater length than height 40 and greater height than width, one of its longest and narrowest sides constituting its bottom, and its top being open. This case is made of any suitable rigid or semirigid material, such as pasteboard, and is provided at 45 one end with a vertical block M, preferably of wood and secured to the end of the case in any desirable manner, as shown, by means of strips of binder's cloth H, glued to the block and to the side of the case. This block M is 50 provided with a longitudinal rib G, having

concave sides, so that it may be conveniently grasped, and I prefer to give the block M the general appearance of the back of a book, so that when the cases are arranged side by side upon the shelf N of a cabinet space is left between the blocks of the several cases for the insertion of the fingers of the user in grasping the block for the removal of the case without disturbing its companions. Indicating characters may, if desired, be marked upon 55 the exposed face of the rib G to generally designate the contents of the case. Such characters appear in the drawings as "PL."

A plurality of pockets a b c d e, as many in number as may be desired, are fitted within 60 the case L. These pockets are preferably of stout Manila paper and are open at their top edges and across one end, as shown, respectively, at p q. I prefer to loosely turn the upper edges of each of the sides of these pockets inwardly, as shown at t u, and these in-turned flaps may be of unequal length, as shown. The fold at the juncture of the side of the pocket and its flap should be but slightly creased, so that normally the flap stands away 65 from the pocket side, of which it forms an integral part, the two flaps t u bearing against each other and thereby normally holding the mouth of the pocket open. By means of this construction the pockets are also held in convenient position for the insertion of slips or 70 clippings, and the contents of the pocket may be readily discharged by removing it from the case and turning it so that its open end is downward, or the hand of the user may be 75 thrust into such end.

The flaps t u serve the further purpose of convenient receptacles for retaining manuscripts, so that in the preparation of literary work a partially-completed manuscript may 80 be thrust into the open end of the pocket and have its upper edge caught under one of the flaps. As further data upon the subject of the manuscript is accumulated it is inserted within the same pocket, and thereby brings 85 the entire subject-matter into one receptacle.

An index form is imprinted upon one of the sides of the case L and is provided with a division or section, as A B C D E, relating to or coöperating with each of the pockets a b c 90

d e, respectively. The several sections of the index may be separated. As shown, this is accomplished by the use of the heavy lines *F*. Each section is united with the top edge of the case *L*. As shown, this is accomplished by continuing the lines *F* to such edge, the several lines being separated, so as to form spaces, as *A' B' C' D' E'*, corresponding, respectively, with the several sections of the index. Upon each of the pockets *a, b, c, d*, and *e* is formed an easily-distinguishable mark or tag *a', b', c', d', and e'*, respectively, the marking of each pocket being opposite the corresponding space *A', B', C', D', or E'*. For greater convenience of tracing the connection between the last-named spaces and the pocket-markings to which they relate lines *f* may be placed upon the flap *t* constituting continuations of the lines *F*.

20 It will be seen that the pocket containing the matter entered in any of the index-sections is readily located by following with the eye the connection between such section and the pocket.

25 I claim as my invention—

1. In a memoranda-file or the like, the combination with a case open at the top, of a plurality of pockets fitted within the case, an index form imprinted upon the side of the case and having a section relating to each pocket, and indicating-marks leading from each sec-

tion to the top of the case, each pocket bearing a distinguishing-tag or the like located opposite the mark leading from the index-section relating to such pocket, substantially as described. 35

2. In a memoranda-file or the like, the combination with a case open at the top, of a plurality of flexible pockets fitted within the case, each pocket being open across the top 40 and having the top edges of its sides loosely inturned, substantially as described.

3. In a memoranda-file or the like, the combination with a case open at the top, of a plurality of flexible pockets fitted within the 45 case, each pocket being open across the top and one end and having at its top an inturned flap, substantially as described.

4. As an article of manufacture, a pocket formed of flexible material and being open 50 across two adjacent edges, its sides being loosely inturned along one of the open edges, substantially as described.

5. As an article of manufacture a filing receptacle or pocket having an open edge and 55 having flexible flaps extending loosely into such opening from its sides, substantially as described.

WALTER L. SMITH.
